UNITED STATES PATENT OFFICE.

STEPHEN J. KRATZEL, OF NORTHAMPTON, PENNSYLVANIA.

TREE-BRANCH HOLDER.

Application filed September 15, 1923. Serial No. 662,920.

To all whom it may concern:

Be it known that I, STEPHEN J. KRATZEL, a citizen of the United States, residing at Northampton, in the county of Northampton and State of Pennsylvania, have invented new and useful Improvements in Tree-Branch Holders, of which the following is a specification.

This invention relates to branch holders 10 designed to facilitate the attachment of branches to Christmas trees.

It is well known that the various types of evergreen trees used at Christmas time are frequently irregular in appearance due 15 to irregular positions of the limbs and at times there will be a relatively large vacant space at one side of the tree; and it is an object of this invention to provide a device which will permit the attaching of 20 a loose limb to the tree to fill in the vacant space and provide a neat appearing artistic tree.

Other objects of the invention will appear in the following description and in the 25 drawings wherein;

Fig. 1 is a fragmentary side elevation of a tree showing parts in section to illustrate the limb attaching device applied.

Fig. 2 is a side elevation of the limb 30 attaching device.

Fig. 3 is a longitudinal section through the limb or branch attaching device.

Fig. 4 a cross section through a modified form of the invention.

Fig. 5 a longitudinal section through a modified form of the invention.

Figure 6 is a detail end view of the tree branch holder.

Referring more particularly to the drawings the improved branch or limb holder comprises a substantially frusto-conical shell 1 which has its base open to receive the butt end of a limb or branch as indicated at 2. The apex of the shell 1 is con-

structed as shown at 3 to snugly fit the 45 head 4 of a screw 5. The screw 5 may be soldered to the body shell 1 as shown at 6 if desired to provide a more rigid connection between the body shell and screw.

The butt end of the limb 1 may be shaved 50 down if necessary to properly fit within the body shell, into which it is forced.

After the limb 2 has been fitted in the body shell 1 the screw 5 is screwed into the trunk 7 of the tree at the desired place, 55 as shown in Figure 1 of the drawings.

In Figure 4 of the drawings a modified form of the invention is shown, in which the body shell 1' is formed of pliable material so as to permit it to be shaped to 60 snugly fit the limb 2', to provide secure connection between the limb and body.

In Figure 5 of the drawings, the body shell 1" has the threaded point 5" formed integrally therewith and in all other respects 65 this modified form is similar to the preferred form previously described. The body shell 1" is preferably oval shaped in cross section as shown in Figure 6 of drawings.

What I claim is:—

1. A tree branch holder comprising a substantially frusto-conical body shell, a screw having a head, the apex of said body shell being constricted to fit said screw head.

2. A tree branch holder comprising a limb receiving body and a threaded attaching member, said body being pliable to permit it to be shaped to fit a tree limb.

3. A tree branch holder comprising a substantially frusto-conical body shell, a screw having a head, the apex of said body shell being constricted to tightly fit the screw, said body shell being pliable to permit it to be shaped to fit a tree limb.

In testimony whereof I affix my signature.

STEPHEN J. KRATZEL.
